UNITED STATES PATENT OFFICE.

LEEMAN S. CROOKSHANKS, OF LAREDO, MISSOURI.

ADJUSTABLE BEARING.

1,100,715.

Specification of Letters Patent. Patented June 23, 1914.

Application filed December 31, 1913. Serial No. 809,733.

To all whom it may concern:

Be it known that I, LEEMAN S. CROOKSHANKS, a citizen of the United States, residing at Laredo, in the county of Grundy 5 and State of Missouri, have invented certain new and useful Improvements in Adjustable Bearings, of which the following is a specification.

My invention relates to improvements in adjustable journal boxes or bearings, having automatic means to compensate for wear upon the engaging parts, and has particular reference to means of this character which are well adapted to be connected with 15 or formed upon a pitman of an engine, of the reciprocating type, either gas or steam, for connecting the same with the crank-shaft, while of course not necessarily restricted to such use.

20 An important object of this invention is to provide means of the above mentioned character, which are simple in construction, inexpensive to manufacture, convenient in use; reliable in operation, strong and durable.

25 A further object of the invention is to provide means of the above mentioned character, which will automatically compensate for the wear upon the engaging parts, in such a manner that a shaft or the like embodied therein, will be held against perceptible lateral or longitudinal improper movement.

30 A further object of the invention is to provide means of the above mentioned character, formed in few and simple parts, which may be readily separated for the purpose of repair or cleaning and assembled in a like manner.

35 Other objects and advantages of this invention will be apparent during the course of the following description.

In the accompanying drawings forming a part of this specification and in which like 40 numerals are employed to designate like parts throughout the same, Figure 1 is a side elevation of apparatus embodying my invention, Fig. 2 is a longitudinal sectional view through the same, Fig. 3 is a longitudinal sectional view taken on line 3—3 of Fig. 1, Fig. 4 is an edge view of the same, and, Fig. 5 is a similar view of the opposite edge.

45 In the drawings, wherein for the purpose of illustration, is shown a preferred embodiment of my invention, the numeral 10

designates a pitman, to which my improved bearing is preferably applied, while of course not necessarily restricted to such use.

50 My improved bearing comprises an inner member or head 11, rigidly connected with the free end of the pitman 10 and preferably formed integral therewith. The member or head 11 is preferably arranged substantially a right angle with relation to the pitman 10 and extends laterally in opposite directions beyond the same for a substantial distance, as shown. One end of the member or head 11 is provided with spaced, apertured knuckles 12 for receiving an apertured knuckle 13, 55 formed upon and preferably cast integral with one end of an outer transverse member, or head 14; as shown. The knuckles 12 and 13 are pivotally connected by means of a removable pin 15, as shown. The oppositely arranged members or heads 11 and 14 are provided with transverse recesses or pockets 16, which are curved in longitudinal and transverse cross-section, as best 60 shown in Figs. 2 and 3. Fitting snugly and 65 rotatably mounted within the recesses or pockets 16 is an enlarged portion 17 of a wrist pin 18, such enlarged portion being curved in longitudinal and transverse cross-section and tapering toward its opposite 70 ends. The wrist pin 18 is rigidly connected with crank-portions 19 of a crank-shaft (not 75 shown).

80 Rigidly connected with the outer end of the lower member or head 14 are spaced inwardly extending arms 20, preferably formed integral therewith. These arms traverse the free end of the inner member or head 11 and extend inwardly beyond the same, as shown. As more clearly shown in 85 Fig. 4, the inwardly extending arms 20 are provided upon their inner faces with enlargements or projections 21, forming inclined shoulders 22, as shown.

90 The numeral 23 designates a compensating or adjusting wedge which is normally mounted upon the exterior surface of the member or head 11, operating below and in 95 slidable engagement with the shoulders 22, as shown. The wedge 23 is automatically urged outwardly to throw the same into 100 action, by a suitably stiff coil spring or 105 springs 24, surrounding a transverse pin 25, carried by the free ends of the arms 20. The springs 24 have their outer ends or 110

turns engaging the arms 20, while their inner ends are suitably connected with a link 26, which is in turn preferably pivotally connected with the wedge 23, as shown at 27.

5 The operation of the apparatus is as follows: When the several parts of the apparatus are assembled, the springs 24 are under tension, and tend to urge the wedge 23 outwardly, for drawing the members or 10 heads 11 and 14 toward each other, such movement of the members 11 and 14 compensating for the wear upon the friction engaging part of the wrist pin 18 and members and heads 11 and 14. With the peculiar 15 shape and construction of the enlarged portion 17 of the wrist pin 18 and the shape of the recess or pockets 16, the compensation of the wear upon said parts prevents both longitudinal and lateral improper 20 movements of the same. When it is desired to remove the adjustable bearing from the wrist pin 18 or the wrist pin 18 from within it, the pin 15 is removed, and upon proper manipulation of the wedge 23, the 25 members or heads 11 and 14 may be readily separated. These members or heads may be just as readily assembled, as is obvious.

While I have shown my adjustable bearing as preferably used in connection with 30 a pitman and crank, with which it is particularly well adapted to coöperate, yet it is to be understood that the invention is in

no sense restricted to this use alone, as the same may be employed with some measure of success in connection with various other 35 elements or combinations thereof.

It is to be understood that the form of my invention herewith shown and described is to be taken as a preferred example of the same, and that various changes in the shape, 40 size and arrangement of parts may be resorted to without departing from the spirit of my invention or the scope of the subjoined claim.

Having described my invention, I claim:— 45

An adjustable bearing comprising co-acting members pivotally connected near corresponding ends, spaced arms connected with the opposite end of one member and traversing the corresponding opposite end of the 50 other member and provided with inwardly extending shoulders, a wedge arranged between the spaced arms and slidably engaging the shoulders and last named member, a pin connecting the outer ends of the arms, and a spring mounted upon the pin and engaging the wedge.

In testimony whereof I affix my signature in presence of two witnesses.

LEEMAN S. CROOKSHANKS.
